UNITED STATES PATENT OFFICE.

JOHN W. REGAN, OF BOSTON, MASSACHUSETTS.

HOSE-NOZZLE.

SPECIFICATION forming part of Letters Patent No. 568,876, dated October 6, 1896.

Application filed April 25, 1896. Serial No. 589,017. (No model.)

To all whom it may concern:

Be it known that I, JOHN W. REGAN, a citizen of the United States, and a resident of Boston, in the county of Suffolk and State of Massachusetts, have invented new and useful Improvements in Hose-Nozzles, of which the following, taken in connection with the accompanying drawings, is a specification.

This invention relates to improvements in 10 hose-nozzles for fire-hose; and it has for its object to throw one or more flat or fan-shaped streams or sheets of water on burning buildings in case of fire, and it is particularly well adapted in theaters or similar halls, where it 15 is desired to prevent a fire on the stage from reaching the auditorium by forming an intermediate liquid curtain, and this may be done either by means of my improved nozzles attached to stationary stand-pipes or forming 20 part of portable hose-pipes, as may be desired.

The device, although particularly well adapted for confining fire in theaters or public halls, &c., may to equal advantage be 25 used for other purposes when it is desired to prevent spreading of fire to adjacent buildings to the one on fire.

The device is also useful for fighting fire direct upon the burning building or materials 30 contained therein, as will hereinafter be more fully shown and described, reference being had to the accompanying drawings, wherein—

Figure 1 represents a side elevation of my invention. Fig. 2 represents a top plan view 35 of the same, showing the slotted cap arranged for throwing sheets of water in two opposite directions. Fig. 3 represents a similar top plan view showing the said cap turned to one side, so as to bring its slits out of alinement 40 with the slits in the ejector. Fig. 4 represents a similar top plan view showing the slotted cap turned to a position for throwing the sheet or sheets of water to one side of the central line of the ejector. Fig. 5 represents 45 a central longitudinal section on the line 55, shown in Fig. 2; and Fig. 6 represents a similar central longitudinal section on the line 6 6, also shown in Fig. 2.

Similar letters refer to similar parts whenever they occur on the different parts of the 50 drawings.

A in the drawings represents the pipe,

which may be of any ordinary form or construction, either a stationary stand-pipe or a portable one attached to the end of a line of 55 hose, as is common in devices of this kind. To the screw-threaded end of said pipe is secured the internally-screw-threaded ejector B, as shown. Said ejector is provided at its upper end with one or more slits b b b, as 60 shown in the drawings. The outer periphery of said slotted ejector is screw-threaded, and on it is adjustably arranged the internally-screw-threaded cap C, provided at its upper end with an inwardly-projecting annular lip 65 C', as shown. Said annular lip C' is provided with transverse slits C" C", which, when the cap C is turned to the position in Figs. 1, 2, and 5, are in alinement with the ejector-slits b b b, so as to cause the sheets of water 70 ejected through the slits b and C" C" to assume fan shapes extending in two opposite directions to the axial line of the pipe A.

At or about right angles to the slits C" are made similar slits C³ C³ C³ in the annular lip 75 C', as shown in the drawings, the opposite portion of the said lip being unbroken, as fully shown in Figs. 2, 3, 4, and 6, and when said slits C³ are in alinement with the slits b b b, as shown in Figs. 4 and 6, the sheet or 80 sheets of water ejected through the slits b b b are caused to extend more to that side where the slits C³ are located as compared with the opposite side of the ring C, thus enabling the firemen, by simply adjusting the position of 85 said ring relative to the slotted ejector B, to cause the fan-shaped streams to be ejected in opposite directions or to one side more than the other relative to the axis of the ejector, as may be desirable, according to the nature 90 and location of the fire to be extinguished or the surrounding objects or buildings to be protected.

If the firemen desire to limit the lateral flow from the slits b in the ejector B, all that 95 is necessary to do is to turn the cap C to the position shown in Fig. 3, so as to cause the slits b to be out of alinement with the slits C" in said cap C.

For the purpose of holding the cap C in 100 any desired position relative to the ejector B, I use a suitable locking or holding device interposed between said parts, which may be either positive or frictional, and for this pur-

pose I have represented in the drawings a yielding frictional spring D, secured, preferably, to the part B and pressing against the part C, as fully represented in Figs. 1 and 6.

5 Having thus fully described the nature, construction, and operation of my invention, I wish to secure by Letters Patent and claim—

1. In a hose-nozzle a pipe having attached 10 to its end an ejector having one or more slits combined with a rotating adjustable cap mounted on said ejector and having transverse slits or notches adapted to be brought in or out of alignment with the ejector-slits substantially as and for the purpose set forth.

15 2. In a hose-nozzle a pipe having attached to its end an ejector having one or more slits combined with a rotary adjustable cap mounted on said ejector and having trans- 20 verse slits or notches adapted to be brought

in or out of alignment with said ejector-slits, and having one or more slits or notches for throwing a sheet or sheets of water to one side of the ejector substantially as and for the purpose set forth.

25 3. In a hose-nozzle a pipe having attached to its end a slotted ejector combined with a laterally or radially slotted adjustable cap and a suitable locking or holding device for holding the parts in their proper adjusted 30 positions substantially as and for the purpose set forth.

In testimony whereof I have signed my name to this specification, in the presence of two subscribing witnesses, on this 18th day 35 of April, A. D. 1896.

JOHN W. REGAN.

Witnesses:

ANBAN ANDRÉN,
THOMAS J. HINES.
